UNITED STATES PATENT OFFICE.

LERoy S. PFOUTS, OF CANTON, OHIO, ASSIGNOR TO THE MILLER PASTEURIZING MACHINE COMPANY, OF CANTON, OHIO, A CORPORATION OF NEW JERSEY.

DESIGN FOR A SUPPORT OR STAND FOR ICE-CREAM FREEZERS.

43,580.

Specification for Design.

Patented Feb. 18, 1913.

Application filed November 19, 1912. Serial No. 732,377. Term of patent 14 years.

To all whom it may concern:

Be it known that I, LEROY S. PFOUTS, a citizen of the United States, residing at Canton, in the county of Stark and State of Ohio, have invented a new and original and ornamental Design for a Support or Stand for Ice-Cream Freezers, of which the following is a specification, reference being had to the accompanying drawing, forming a part hereof.

In the drawing the figure is a side elevation of a support or stand for an ice cream freezer showing my new design.

I claim:—

The ornamental design for a support or stand for an ice cream freezer, as shown.

LERoy S. PFOUTS.
